FIG. 1

FIG. 2

FIG. 3

FIG. 7

FIG. 5

FIG. 4

FIG. 6

FIG. 8

FIG. 1 is a perspective view of a light deflector showing our new design;

FIG. 2 is a cross-sectional view thereof taken along lines 2—2 of FIG. 1;

FIG. 3 is a front view thereof;

FIG. 4 is a rear view thereof;

FIG. 5 is a view showing one end thereof;

FIG. 6 is a view showing the other end thereof;

FIG. 7 shows a bottom view thereof; and

FIG. 8 shows a top view thereof.

The heavy solid lines represent contours on the obverse side of a transparent object and the light solid lines represent contours on the reverse side of the transparent object. The alternating solid and dashed lines of FIG. 2 are to indicate transparent material shown in cross section.

We claim:

The ornamental design for a light deflector for a photographic camera, substantially as shown and described in the foregoing.
